UNITED STATES PATENT OFFICE.

CARSTEN ROYEM, OF CHICAGO, ILLINOIS, ASSIGNOR TO HERBERT W. GUETTLER, OF CHICAGO, ILLINOIS.

BARKING DRUM.

Application filed November 15, 1926. Serial No. 148,411.

This invention relates to barking apparatus, and more particularly to barking drums.

There are three general forms of construction of barking drums which I will discuss briefly in connection with my invention. One form employs bars of angle cross-section, or a combination of angle bars and channel bars, which are mounted within the drum with their sides directed inwardly thereof. This form has been found to be unsatisfactory as it causes excessive splitting and brooming of the logs, which is a serious objection.

The second form of drum under consideration has channel bars mounted closely adjacent each other to leave between the bars narrow openings or slots for escape of the removed bark, the open faces of the bars being disposed outwardly of the drum and the base or bight portions being directed inwardly of the drum radially thereof. This produces a drum, the inner surface of which is practically continuous so far as tumbling the logs or having any effect in removing the bark from the logs is concerned. In this form, when the drum is rotated, the mass of logs slides within the drum, without positive tumbling. While this form of drum avoids the objection of excessive splitting and brooming of the logs, its output is, as experience has shown, greatly limited.

In the third form of drum, the removal of the bark is effected by the combined action of the logs rubbing together and the bars of the drum acting upon the logs. This form of drum is illustrated in the patents to Herbert W. Guettler, numbered 1,311,225 and 1,311,226, for barking drum, issued July 29, 1919. In this form the bars are of skeleton

formation and U-shape in cross-section. These bars are spaced an appreciable distance apart to form pockets permitting the corners of the logs to be engaged by the bars, and the bight portions of the bars are disposed inwardly of the drum radially thereof, and are smooth and rounded. During rotation of the drum the logs are subjected to a positive rolling and tumbling action and are caused to strike upon and slide over the rounded inner portions of the bars. This serves to very quickly break and loosen the bark and remove it from the logs. This action is supplemented by the rubbing to-

gether of the logs so as to quickly rub off any adhering particles of bark. This drum thus combines all of the desirable features of the drums of the first two types while avoiding the objections to such drums, and has the additional advantage of light but strong and durable construction.

The type of drum disclosed in the Guettler Patent 1,311,226 above identified has been found to be highly efficient in use, but is subject to one objection. The logs which are ordinarily barked in drums vary in length from two to four feet, being occasionally in excess of four feet in length, the drums being, say, ten or twelve feet in diameter. It has been found that logs of certain lengths will sometimes wedge or jam endwise between the bars of a drum of the type disclosed in the Guettler Patent 1,311,226. This is due to the shape of the U-bars and the relation between the complementary faces of these bars.

I have found that by constructing and arranging the bars in a certain way, it is possible to produce a barking drum which will thoroughly bark logs of any length, between the practical limits, without any wedging or jamming thereof. My drum thus combines all the advantages of the third type of drum above discussed with the additional advantage of eliminating wedging or jamming of the logs.

In order to more clearly illustrate the differences and advantages of my drum over the Guettler drum, I have shown several diagrams of U-bars as used in the two drums, respectively.

In the drawings:

Fig. 1 is a diagram of two of the bars of the Guettler drum, illustrating the relation between the U-bars;

Fig. 2 is a diagram of one of the U-bars, enlarged;

Fig. 3 is a fragmentary sectional view of the Guettler drum, illustrating the positions assumed by logs of different lengths;

Fig. 4 is a diagram of two of the bars showing a log jammed between them;

Fig. 5 is a diagram of two of the U-bars of my drum illustrating the relation between the bars;

Fig. 6 is a diagram of one of the bars of my drum;

Fig. 7 is a side elevation of a drum constructed in accordance with my invention;

Fig. 8 is a fragmentary sectional view of my drum illustrating the positions assumed by the logs;

Fig. 8^a is a diagram showing the angle between the end of a log of extreme length and the side of a bar of my drum;

Fig. 9 is a fragmentary perspective detail of the construction of my drum.

Referring to Figs. 1 and 2 of the drawings, it will be noted that the opposed faces a' of adjacent U-bars a of the drum A (which is from ten to twelve feet in diameter) are disposed at an angle of approximately 45° to each other, and that the faces a' of each U-bar are disposed at an angle of approximately 50° to each other and at an angle of approximately 25° to the radius $e-f$ of the drum.

The bars a are of skeleton formation, being constructed preferably of rolled steel. In practice the drum is from ten to twelve feet in diameter, as before indicated, and is filled about half full of logs to be barked, the drum being rotatably supported and rotated in any suitable or preferred manner, several of which are well known in this art. It has been found that some logs of certain lengths will wedge or jam endwise between the bars of this drum. This is due to the following:—The angle of the sides of the bars is such, as experience has shown, that logs of certain lengths can and sometimes do become jammed between complementary faces thereof as shown in the instance of the longest log in Fig. 3. As shown in Fig. 4, the ends of the log are actually deformed in this jamming action, particularly when the weight of other logs on top of it is imposed thereon, and under these circumstances the log becomes so tightly lodged as to require extraneous means to dislocate it. Obviously operating efficiency of the drum is seriously interfered with, by logs jamming in the manner stated.

In constructing my drum, the bars have their sides 2 disposed at an angle of approximately 90° to each other, the angle between the outer face of each side and the radius $a-b$ of the drum being approximately 45° . In my bar the angle between each of the sides 2 and the radius $a-b$ is much greater than 25° as in the case of the Guettler bar above discussed, being approximately 45° as shown in Fig. 6, though this angle can be varied within certain limits provided it is sufficient to produce a relieving angle between the complementary faces of the bars and the ends of the log. In a ten or twelve foot drum, for instance, bars of this type would lie with adjacent faces approximately 75° to each other, as shown in Fig. 5.

I have found this angle of 45° to the radius sufficiently great, in a drum having an

interior diameter of ten feet, to be relieving for logs of a length somewhat more than five feet, which is ample as it is very exceptional to bark logs five feet long in a drum. By "relieving" I mean that, with a log contacting with two complementary bar faces, the angle between the face of the bar and the log end contacting with it diverges toward the drum center and is such as to prevent jamming of the log, permitting the log to readily move from between the bars on continued rotation of the drum. This will be clear from Fig. 8, Fig. 8^a showing the decided angle in the case of the longest log. In fact, only the edge of the log end contacts with the inclined surface of the bar. This eliminates all possibility of jamming and yet retains the desirable positive tumbling action hereinbefore referred to.

It will be appreciated that it is within the broad aspects of my invention to dispose but one side of the bars at this relieving angle, it being obvious that relief of a log at one end only could be relied upon. By this same token, it is also within the broad aspects of my invention to make alternate bars with sides at relieving angles and the remaining ones with the non-relieving angles of the prior art.

In actual construction each of the bars 1 is provided at each outer edge with an outwardly extending base flange 4. The drum includes the bars 1, the flanges 4 of which are secured by riveting, or in any other suitable or preferred manner, to annular hoops 5 of angle or any other suitable or preferred cross-section. The bars are disposed in parallel relation and are spaced an appreciable distance apart to provide pockets between the bars of proper breadth to ensure that the bars will contact with the ends of the logs for positively tumbling them during rotation of the drum. At suitable intervals I provide pairs of angle hoops 6 arranged with their flights projecting outwardly from the drum and disposed opposite and adjacent each other. Solid rings 7 are positioned between the opposed flights of the pairs of hoops 6, the rings and the flights of the hoops being secured together by riveting or in any other preferred manner. The hoops 6 are secured to the bars 1 in the same manner as hoops 5 and the rings may be made to travel upon supporting rollers arranged in a known manner for rotatably supporting the drum. The drum may be rotated by means of driven pinions (not shown) meshing with a gear ring 8 secured to the drum in the same manner as the rings 7 are secured. I also contemplate supporting and driving the drum by chains, or in any other suitable or preferred manner well known in this art.

I claim:

1. In a barking apparatus, a rotatable

drum, and a plurality of tumbling devices mounted within the drum and spaced apart an appreciable distance forming pockets for catching the corners of logs for tumbling the same, said devices having their lateral faces inclined toward each other inwardly of the drum, the angle between said inclined faces being appreciably greater than 50°.

5 2. In a barking apparatus, a rotatable drum, and a plurality of tumbling devices mounted within the drum and spaced apart an appreciable distance forming pockets for catching the corners of logs for tumbling the same, the angle between the complementary faces of said devices being relieving to prevent jamming of the logs.

10 3. In a barking apparatus, a rotatable drum, and a plurality of tumbling devices mounted within the drum and spaced apart an appreciable distance forming pockets for catching the corners of logs for tumbling the same, the angle between the opposed faces of adjacent devices being appreciably greater than 45°.

15 4. In a barking apparatus, a rotatable drum and a plurality of tumbling devices mounted within the drum and extending inwardly thereof, at least one lateral face of the respective tumbling devices being disposed at an angle appreciably greater than

25° to a radius of the drum intersecting the apex of said device.

5 5. In a barking apparatus, a drum for barking logs of from two to approximately five feet in length, said drum including a plurality of spaced U-bars extending inwardly of the drum and each having a side face inclined to a radius of the drum intersecting the apex of the bar, the angular relation between the side face to said radius being such that the angle between the end of a log contacting with said side face and the complementary face of a cooperating bar diverges toward the center of the drum.

10 6. In a barking apparatus, a drum for barking logs of from two to approximately five feet in length, said drum including a plurality of spaced U-bars extending inwardly of the drum and each having a side face inclined to a radius of the drum intersecting the apex of the bar, the angular relation between the side face and said radius being such that the angle between the end of a log contacting with said side face and the complementary face of a cooperating bar is relieving.

In witness whereof, I hereunto subscribe my name this 2nd day of November, 1926.

CARSTEN ROYEM.
